DESIGN FOR A PERFUME BOTTLE

Main R. Bocher, New York, N. Y.

Application August 25, 1947, Serial No. 141,055

Term of patent 14 years

(CL. D58—8)

To all whom it may concern:

Be it known that Main R. Bocher, a citizen of the United States, residing at New York, in the county of New York and State of New York, has invented a new, original, and ornamental Design for a Perfume Bottle, of which the following is a specification, reference being had to the accompanying drawing, forming part thereof.

Fig. 1 is a side view of a perfume bottle, showing my new design,

Fig. 2 is a view looking downward at an angle toward the top of the bottle, and,

Fig. 3 is a top plan view thereof.

The dominant features of my design reside in the portions shown in full lines.

I claim:

The ornamental design for a perfume bottle, as shown and described.

MAIN R. BOCHER.
